COOKING VESSEL

Eduard Bay, Hohlstrasse, 5412 Ransbach,
Westerwald, Germany

Continuation of design application Ser. No. 17,397, May 28, 1969. This application July 31, 1970, Ser. No. 24,249

Term of patent 14 years

Int. Cl. D7—02

U.S. Cl. D44—1

FIG. 1.

FIG. 2.

FIG. 3.

FIG. 4.

FIG. 5C.

FIG. 5A.

FIG. 5B.

FIG. 6A.

FIG. 6B.

FIG. 6C.

FIG. 1 is a top plan view of a cooking vessel showing my new design;

FIG. 2 is a bottom plan view;

FIG. 3 is a side elevational view;

FIG. 4 is an end elevational view;

FIGS. 5a, 5b, and 5c are developed views of an enlarged scale of the areas within the boxes shown in FIG. 1 and designated 5a, 5b and 5c, respectively; and

FIGS. 6a, 6b and 6c are developed views on an enlarged scale of the areas within the boxes shown in FIG. 2 and designated 6a, 6b and 6c, respectively.

This application is a continuation of my copending application Ser. No. D. 17,397, filed May 28, 1969 and now abandoned.

I claim:

The ornamental design for a cooking vessel, as shown and described.
